UNITED STATES PATENT OFFICE.

CHARLES ANDERSON, OF SOUTH BEND, INDIANA, ASSIGNOR TO THE SOUTH BEND IRON WORKS, OF SAME PLACE.

SIDE-HILL PLOW.

SPECIFICATION forming part of Letters Patent No. 365,162, dated June 21, 1887.

Application filed January 27, 1887. Serial No. 225,726. (No model.)

To all whom it may concern:

Be it known that I, CHARLES ANDERSON, of South Bend, in the county of St. Joseph and State of Indiana, have invented certain new and useful Improvements in Hillside-Plows; and I do hereby declare the following to be a full, clear, and exact description of the invention, such as will enable others skilled in the art to which it appertains to make and use to the same.

My invention relates to side hill plows, and more particularly to a type in which a single mold-board with its attached share is made to swing from one side of the beam to the opposite side of this beam to permit a return-furrow to be made by the plow, the primary object of my invention being to provide a reversible pointed turf-slicer, which is adapted to change its lower cutting-edges automatically when the mold-board and share are made to change their position to cut furrows in reversed directions, the shaft on which the turf-slicer is secured to reverse its edges being provided with an actuating device that permits an adjustment to afford greater or less lateral swinging motion of the plow-beam when the mold-board and share are reversed.

A further object of my invention is to provide a vertical box-swivel bearing in the body of the beam of the plow, to afford a stable pivot-joint where the beam connects to the standard.

A further object is to furnish a double-faced landside, which is adapted to be firmly locked to the lower portion of the standard when these parts are in secured adjustment, the lock being effected by a hook-connection without the use of bolts or screws.

A further object is to provide means whereby a simultaneous change of position relatively of the beam, slicer, and handles is effected when the mold-board and its attached share are released and made to swing into an adjusted or secured position on the opposite side of the beam, to permit the plow to be operated in reversed direction.

A further object of my invention is to furnish a double-pointed lozenge or rhomb shaped turf-slicer, that by its peculiar form permits a reversal of position on a revoluble supporting-shaft, and thus afford a duplicate slicer for use

when the opposite edges have been dulled or injured by use or accident.

With these objects in view my invention consists in certain features of construction and combinations of parts, that will be hereinafter fully described, and pointed out in the claims.

Referring to the drawings making a part of the specification, Figure 1 is a side and rear elevation of the device in perspective, taken on the land side of the plow. Fig. 2 is a plan view of the plow, illustrating the swinging action of the mold-board and share when a change of position of these parts is effected. Fig. 3 is a rear elevation of the plow. Fig. 4 is a vertical longitudinal section of the plow. Fig. 5 is a view of the rear end of the plow-beam and standard of the plow, the standard and attached beam being broken into section to show the cam, the forked dog, and slicer-shaft that is boxed in the standard. Fig. 6 is a plan view of the plow mold-board. Figs. 7, 8, and 9 are detached views of different parts.

A represents the beam of the plow. It is made preferably of metal, and is given an approved form to insure strength as well as lightness of its body. The forward end of the beam A is provided with the usual depth-wheel, a, that is secured to rotate on a vertical bar, a', which is perforated with spaced holes a'', to permit a change of horizontal plane of the wheel. The hook b is forked at its rear end to embrace the sides of the beam A, which has a series of spaced perforations, b', made to receive a transverse bolt, b'', and permit a change of adjustment of the draft-hook b, as may be required to regulate the draft of the plow.

At a point, B, on the beam A a circular enlargement or boss is made on its body to allow a slightly-conical round orifice, B', to be formed in the boss B, this aperture being tapered from its top edge to the bottom. The base-wall or shoulders c of the hole B' is centrally perforated for the reception of the bolt c'. A barrel-washer, C, is made with two projecting circular flanges, c' c'', that project from the centrally-perforated body C, to have a neat moving fit within the orifice B' at the upper and lower edges of this tapered hole. The lower end of the barrel-washer C has a short cylindrical portion, c'', made to project

below the lower flange, c^3 , of the washer and have a contact upon the upper surface of the standard D. The standard D, just mentioned, is made of metal, and is preferably given the 5 form exhibited in the drawings. The upper part, D', consists of a center plate, which is web-flanged on its edges to afford strength and lightness, the lower part, D ^{2} , consisting of a single plate, as shown. The barrel-washer C 10 has its lower end that projects through the orifice made for its reception in the beam A of such a relative length as to afford a contact-bearing upon the upper face of the standard D, so that the bolt g, which is inserted through 15 a hole in the projecting end g' of the standard D and penetrates the center of the barrel-washer C, will, by means of its head g ^{2} , formed on it to engage the standard D, and a securing-nut, g ^{3} , adjusted to bear firmly on the upper 20 surface of the barrel-washer, hold the beam A in secured swinging adjustment with the upper face of the standard D, the nut being forced to seat firmly, and thus prevent accidental displacement of the bolt and the connected 25 parts held by it.

The mold-board E and the share E' are bolted together in secure manner, and are of approved form of construction. The mold-board and share are pivoted to the front and rear ends 30 of the lower part, D ^{2} , of the standard to permit the semi-revolution of these parts on the pivotal points of suspension d d', as shown in Fig. 4. The front ends of the connected share and mold-board have their pivot-point d' 35 formed on the standard D, the pivot that projects from the front edge of the standard engaging a proper perforation made in a shoulder formed on the re-enforce plate E ^{2} , which holds the mold-board and share in connection 40 by countersunk bolts inserted through these connected parts. The rear portion of the mold-board E is pivotally connected by the T-shaped bracket-arm F', which is secured to the mold-board and made to project a sufficient distance 45 to permit an engagement of the socket, formed in its free end e, with a cylindrical projection made on the rear face of the lower part of the standard D. The stay-bolt e' is provided to hold the arm F' in secured adjustment with 50 the standard D, it being made to engage with the arm F' and a lug, e ^{2} , formed on the inner surface of the re-enforce plate E ^{2} , to stiffen the arm F' and prevent a rearward springing action of this arm. The standard D has an enlargement 55 made on its body to provide sufficient material to allow the formation of an inclined circular aperture, G, that perforates it from front to rear edge, the "pitch" or degree of inclination of this orifice being such 60 as to give a proper position to the shaft H, which is inserted to rotate in it.

The forward end of the shaft H is flattened to provide a seat to receive the slicer-blade H'. The turf-slicer blade H' is given a lozenge or 65 rhomb form, as shown in Figs. 1 and 4. It is secured in place on the shaft H by a bolt inserted through corresponding holes formed in

the end of the shaft and the slicer, the bearing end of the shaft lying between parallel shoulders formed upon the rear face of the 70 double-pointed slicer H', to prevent a lateral movement of the attached slicer.

The length of the shaft H is so proportioned to the projecting point of the plowshare that the point of the diamond-shaped slicer H' will 75 be slightly in advance of the point of the plow-share.

The body of the slicer H' is made concave on its face, in a manner to afford a shear-edge on each side, these edges being rendered more 80 effective by a bevel formed upon the rear face of the rhombus, to provide a jointer or knife-edge, which inclines at such an angle rearwardly that the blade will have a shear action upon the stiff turf or surface soil to slice it in 85 advance of the plowshare, and by its efficient action greatly aid the operation of plowing. The double point provides a duplicate slicer, that can be substituted for the one first used 90 when it is dulled or injured by use or accidental contact with a rigid obstruction.

The rear end of the shaft H is made to project through the standard-body to receive a cam, I. This cam consists, essentially, of an oval disk, i, of a proper thickness, which is provided with an integral flange, i', that projects radially from its rear edge sufficiently to form an abutment for the inclined depending limb, A ^{2} , formed integrally upon the rear end of the plow-beam A. The degree of inclination of this limb A ^{2} causes it to lie with its rear face in a plane parallel to the opposed face of the standard D, the collar or flange i' being located between these opposed surfaces. The disk i of the cam is held in place to have working contact with the side walls of an oblong slot made through the limb A' to receive this disk. The cam I is slotted on its lower side to allow it to embrace the shaft H and be moved a limited distance vertically. The front face of the cam I has a parallel edged plate or arm, i ^{2} , made to extend from the edge of its disk i to engage shoulders or flanges made on the inner face of the forked arm J, which is also given a variable position upon the shaft H immediately 105 in front of the cam J, and is adjustably secured to the same by the set-screw i ^{3} .

The portion of the arm J, which has secured contact with the arm i ^{2} of the cam I is attached to this arm by a stud-bolt, i ^{4} , which projects from the face of the arm to enter and slide in a short slot, i ^{5} , made in the upper end of the forked arm J.

The lower portion of the arm J is slotted to form two parallel limbs k, the slot k thus produced permitting the insertion between the limbs k of the free end of the lever K', that is a forward projection from the tripping-plate K, which is seated upon a rearward extension, m, of the standard D.

The tripping-plate K is pivoted at m to vibrate laterally, and give a limited rocking motion to the shaft H, as will be explained.

Upon the tripping-plate K the handle-car-

rier L is mounted. This piece L is pivoted at the front end, *n*, to the standard D, a lug or boss extension formed on this piece L being held to move by a bolt, *n'*, inserted through this end and also through an ear, *n''*, formed integrally on the standard D immediately above it, the bolt *n'* being secured by a nut, *n'''*, that is seated in a slot formed at a proper point in the body of the standard D below the face on which the handle-carrier L is located. The carrier-plate L has the vertical flanges *o* made to project from its face to receive and retain in fixed contact the handles M, these flanges *o* being given a sufficient angular divergence to hold the handles M in proper position with regard to each other. The inclination of the carrier-plate L is such as to project the handles diagonally upward in the same plane a proper distance for convenient use.

The tripping-plate K has the laterally-extending hooks *p p'* bolted to recessed ears at the points *p²*, these hooks *p p'* engaging the edge of the bracket-arm F' alternately as the mold-board is adjusted to either side of the beam A. A spring-latch, *r*, is made to project from the under surface of the standard D to engage notches *r' r''*, made to receive the beveled edge of the free end of this spring-latch *r*, the notches being made to register with the spring-latch when either one or the other of the hooks *p p'* are in locked contact with the bracket-arm F', as before mentioned.

It is evident that the pressure of the foot of an operator exerted upon the edge of the hook *p* or *p'* that is free will cause a release of the opposite engaged hook, and permit a reversing movement of the mold-board and share by simply raising the plow by its handles and swinging the same laterally. A lowering of the plow will cause the bottom of the landside to seat upon the ground and effect a latching of the mold-board with the hook that is in engaging contact with the bracket-arm F'.

While the latching movement just described is being executed the engagement of the lever K' with the limbs *k* of the arm J will give a rocking motion to the shaft H, which will be so graduated as to cause the proper alignment of the slicer H' with the share below it to cause it to cut properly. The plate L that supports the handles M is acted upon by the vibration of tripping-plate K, as the point of pivotal connection effected by the bolt *s* is a short distance to the rear of the pivot-bolt *m'*, and a consequent leverage is afforded to move the handles laterally, they being pivoted to vibrate on the bolt *n'*. This movement sidewise of the handles is necessary to bring them alternately in proper relative position to operate effectively when the plow is used as a right or left hand plow, as occasion demands. The partial rotation of the shaft H and cam I causes the bearing of this cam-disk upon the contact-surface of the depending limb of the beam A to give a side motion to this end of the beam, the point of pivotal motion being the bolt *c'* that connects the beam and stand-

ard of the plow. It is evident that a movement of the tripping-plate to release one of its latches *p p'* will cause the simultaneous adjustment of the beam A, slicer-blade H', and handles M, and that this movement will be effected while a change of the position of the mold-board is being executed, the adjustment of these four elements being made with equal facility when the plow is being changed to use on either side of the beam.

The sliding plate *i*, that is fixed to the cam and has an adjustable connection with the cam-disk *i*, is provided to furnish a means of changing the throw of the cam, as by setting the cam higher or lower the throw of this cam and the lateral vibration of the attached plow-beam will be increased or diminished, as the case may be; and the position of the slotted arm J 85 may also be changed to throw the beam farther to one side or the other of the pivotal center of the tripping-plate K by slackening the set-screw *i'*, then moving the arm laterally on the supporting-shaft H, and resetting the tightening-screw to secure the adjustment.

The landside O is secured to the lower edge of the standard D, it being channeled longitudinally to fit a correspondingly-shaped tongue, *t*, made on the foot of the standard. 95 The tongue and channel of these engaged parts are given a regular taper, being thicker at the rear end or heel of the standard and regularly decreasing in thickness toward the front edge of the standard, to form a close fit of the double landside upon its seat when it is in position thereon.

A perforation or loop is made in the front end of the double-walled landside O, to receive the dowel *d'*, that also affords a pivot-point for 105 the share and mold-board of the plow. A shoulder, *u*, is formed on the walls of the landside O, to abut against the front edge of the standard D, and a hook, *u'*, is formed on the lower surface near the rear end of this standard, to enter the loop formed by securing a cross-bar transversely between the walls of the landside at a proper point for such engagement. The sides of the landside O are formed alike, and these side faces are made alternately 115 to line with the vertical wall of the plowshare as these similar faces of the double landside are brought successively into position with this upright face of the plowshare.

The lower surface or tread of the landside O 120 is made to droop slightly toward the rear end to give the point of the plowshare a proper dip to hold it at a proper depth, which is controlled by the position of the depth-wheel at the forward end of the beam.

Slight changes might be made in the form of construction of the several parts of my improved plow without departure from the spirit or exceeding the scope of my invention. I do not therefore desire to restrict myself to exact 130 forms shown; but,

Having fully described my invention, what I claim as new, and desire to secure by Letters Patent, is—

1. In a side-hill plow, the rhomb or lozenge shaped double - pointed slicer - blade having shoulders on its rear face and adapted to be reversed in position endwise, its face concaved from each corner to the center and having a bold beveled edge to provide a shear cut, substantially as set forth. 55
2. In a side-hill plow, the combination, with a standard having projections integral thereto with, of a double-walled landside having loops to engage said projections, the front wall of said landside adapted to rest in contact with the front face or toe of the standard. 60
3. In a side-hill plow, the combination, with a plow having an upwardly-projecting standard and a beam pivoted to the standard, and having a looped depending rear end, the latter resting behind the standard, of a cam engaging said depending rear end of the beam and adapted to move the beam sidewise, substantially as set forth. 65
4. In a side-hill plow, the combination, with a plow having an upwardly-projecting standard and a beam pivoted to said standard, and having a rear depending end resting behind the standard, of a variable cam engaging said rear depending rear end, and devices for rocking the cam, substantially as set forth. 70
5. In a side-hill plow, the combination, with a pivoted plow-beam and laterally-vibrating handles, of a tripping-plate having a forwardly-projecting arm adapted when moved laterally to move the beam and handles, substantially as set forth. 75
6. In a side-hill plow, the combination, with a pivoted plow-beam, a slicer-supporting shaft journaled in the standard, and two plow-handles supported to vibrate laterally, of actuating mechanism adapted to rock the shaft and vibrate the plow-handles and pivoted beam, substantially as set forth. 80
7. In a side-hill plow, the combination, with a vertical standard, of a horizontal beam having a vertical socket extending through same, a shoulder projecting into the socket at the lower end thereof; a cylindrical box located in the socket and resting on the shoulder, and a bolt passing through the box and secured to the standard. 85
8. In a side-hill plow, the combination, with a beam pivoted to swing on a standard, and a standard, of a boxed shaft, a double-pointed

reversible slicer-knife fixed to the shaft, and a means of turning the shaft to properly adjust the opposite edges of the slicer when the mold-board and plowshare and beam are changed in position, substantially as set forth. 90

9. In a side-hill plow, the combination, with a vertical standard and a pivoted beam that has a looped rear end, of a shaft supported in the standard, a double - pointed slicer-knife fixed to the shaft, and a cam secured to the rear end of this shaft to vibrate the beam sidewise when the shaft is turned or rocked in its box-support, substantially as set forth. 95

10. In a side-hill plow, the combination, with a pivoted beam and handles, of a tripping-plate having hooks for locking the mold-board, and a forwardly-projecting arm for rocking the beam, substantially as set forth. 70

11. In a side-hill plow, the combination, with a standard, a pivoted beam, laterally-swinging handles, and a rolling shaft carrying a slicer or colter, of a device for simultaneously moving the handles and beam and rolling the shaft, substantially as set forth. 75

12. In a side-hill plow, the combination, with a pivoted plow-beam, a slicer-supporting shaft journaled in the standard, and plow-handles supported to vibrate laterally, of a mold-board and plowshare having swinging connection with the standard, and mechanism that latches the mold-board, vibrates the plow beam and handles, and rocks the slicer on its shaft at the same time, substantially as set forth. 80

13. In a side-hill plow, the combination, with a standard, a pivoted beam having a depending rear end, a slicer-shaft, an adjustable cam and forked arm fixed to the rear end of this shaft, of a pivoted tripping-plate, an arm on this plate to engage the forked arm, two side-projecting hooked arms, and a pivoted handle-carrier plate, the tripping - plate being adapted to rock the slicer-shaft and vibrate the beam and handles simultaneously, substantially as set forth. 90

In testimony whereof I have signed this specification in the presence of two subscribing witnesses.

CHARLES ANDERSON.
